CLAIM

The ornamental design for a stir stick, as shown and described.

DESCRIPTION

FIG. 1 is a left side elevation view of a stir stick showing my new design;

FIG. 2 is a front elevation view thereof;

FIG. 3 is a right elevation view thereof;

FIG. 4 is a rear elevation view thereof;

FIG. 5 is a top plan view thereof;

FIG. 6 is a top rear perspective thereof;

FIG. 7 is a top front perspective view thereof;

FIG. 8 is a bottom front perspective view thereof; and,

FIG. 9 is a bottom rear perspective view thereof.

The regularly broken line portions of FIGS. 1-4 and 6-9 show unclaimed subject matter only and form no part of the claimed design.

The dash-dot-dash broken line portions of FIGS. 1-4 and 6-9 indicate the boundary of the claim and form no part of the claimed design.

1 Claim, 2 Drawing Sheets
